UNITED STATES PATENT OFFICE.

JACOB E. BLOOM, OF BROOKLYN, NEW YORK.

ELECTRICAL PROCESS AND APPARATUS FOR THE DYEING OF FURS AND OTHER MATERIALS AND THE PRODUCTS RESULTING THEREFROM.

1,338,353.

Specification of Letters Patent. Patented Apr. 27, 1920.

Application filed September 30, 1919. Serial No. 327,580.

To all whom it may concern:

Be it known that I, JACOB E. BLOOM, a citizen of the United States, residing at Brooklyn, city of New York, county of 5 Kings, State of New York, have invented certain new and useful Improvements in Electrical Processes and Apparatus for the Dyeing of Furs and other Materials and the Products Resulting Therefrom, of which 10 the following is a specification.

This invention relates to an electrical treatment in dyeing processes and to the apparatus therefor, and to the products thereof; and is illustrated herein particularly in 15 the dyeing of furs, pelts, hair and other animal productions; and has for its objects, the fastening or fixing of the dyestuffs or components thereof, upon the hair or animal fiber by electrical adsorption and electric 20 reaction forces in addition to ordinary absorption and chemical affinity and the like; and thereby more effectively fastening and fixing the dyestuffs and at lower temperatures. Other objects are set forth 25 in the body of the specification and claims.

In my application for Letters Patent Serial No. 205,228, filed December 3rd, 1917, for process, etc., for electrical treatment in the dyeing of fibers, and likewise in my 30 Serial No. 225,229, filed December 3rd, 1917, and Serial No. 250,814, filed August 21st, 1918, I describe and claim the application of alternating currents and A. C. fields or supply whereas herein, I use direct current 35 supply, this process herein described being an alternative process and means to attain the same or similar products or ends; and it will be understood that the A. C. fields applications and method therein described 40 are likewise applicable or adaptable herein, and vice versa the A. C. applications and methods herein described are applicable therein. And also the D. C. applications and apparatus described in my application 45 Serial Number 327,579 for patents filed simultaneously, herewith pertaining to an electrical process and apparatus for compounding liquids and gases.

This invention, in general, practically 50 adapts and applies, with improvements, the principle, that when particles are brought under insulated conditions, into contact with only the one pole or terminal of a direct current supply or source of electricity 55 and the like, of a sufficiently high voltage

and amperage, then the said particles will take up an electric charge of the same sign as said contact pole or terminal and with varying degree of rapidity, depending principally upon their electric or electrostatic capacity; and influenced by other conditions herein recited, including such as dryness, temperature and resistivity.

As a process, this invention, in general, 60 consists in electrifying or conferring an electric charge of one sign only, upon the fur or fiber and the like, in a dry state under insulated conditions; advantageously positive for furs; and then bringing into contact therewith, (as by immersion therein 65 or daubing and painting or spraying and the like therein), under insulated conditions, the dyestuffs liquor and the like, the liquor being either electrically neutral, or previously oppositely electrified under insulated conditions; and thereafter advantageously continuing the contact of the immersion, where such has taken place in a mordant dye liquor, with the electrically 70 charging thereof with one sign only, advantageously of a sign opposite to that, if any, taken up by the fur or fiber by mere immersion in the liquor without electrification from external source. Otherwise, I 75 conduct and complete the dyeing as at present.

This electrical treatment is readily adaptable in the various present processes of dyeing,—in some of which there is only one immersion as with direct dyestuffs; and in 80 others there is first immersion in a mordant liquor, followed by another immersion in a dyestuff liquor; I apply the electrical treatment in the former immersion as well as in the latter, advantageously drying the fiber 85 between the two operations; and advantageously conducting the immersions at lower temperatures and for shorter periods of time, than are commonly employed in present methods.

As a process, the invention in general 90 further advantageously consists in first largely freeing the fur or fiber from air and moisture and the like, in a vacuum or near vacuum and then electrifying the fur 95 or fiber with one sign only under insulated conditions in the vacuum or near vacuum; and then bringing into contact therewith the dyestuff liquor as aforesaid, advantageously in a vacuum, and the liquor being 100 105 110

previously separately advantageously oppositely electrified; all under insulated conditions.

- As a process, the invention in general 5 after removing most of the liquor from the fur and the like as at present further advantageously consists in drying the furs and the like in a closed chamber with a stream of warm air or ozone or oxygen or like gases 10 circulating therethrough advantageously ionized and oppositely electrified to assist oxidation advantageously in cases of dyeing where oxidation from the atmosphere is now wholly or in part relied upon.
- 15 As a product, the invention in general consists of a fur or fiber, or down and the like or other material dyed with fast stable electrically adsorbed and electrically reacted dyestuffs and electrically fixed ions and col- 20 loids and particles of dyestuffs from solution thereof, homogeneously fixed in and upon the hair, or feather, or fiber and the like and advantageously the hide or skin also, where such is desired, and in non- 25 strained equilibrium and of increased density and increased stability and durability of color and preservation of glossiness of the fur as regards or against deterioration from light, heat, moisture and time, *i. e.*, increased 30 as compared with dyeing without the electrification process, and with diminished hy- 35 groscopic property.

As an apparatus the invention in general 40 consists of a vessel, vat, pot, kier or other chamber or the like, for the dyeing purpose 45 stated, which may be advantageously of good electrical conducting metal material, with insulator supports; with means for supplying to circulating in and withdraw- 50 ing from the chamber of said vessel a suitable dyestuff liquor; with means of controlling the temperature of said liquor, to temper- 55 atures suitable for the material to be dyed and to the dyestuffs, advantageously low temperatures for furs; with means for immersing in and withdrawing from said 60 chamber and liquor, the materials to be dyed under insulated conditions; and with means of supporting the materials therein on elec- 65 trifier plates or shelving and the like of good electrically conducting material and advantageously separately removable, and which I call the extension of the terminal; with means of electrically connecting the support- 70 ing plates by an insulated wire with what I call the electrifier apparatus to wit, with one terminal or pole of a direct current supply, the other pole being simultaneously earthed; with a pole changing switch in said line 75 and advantageously with voltmeter, ammeter and a rheostat or resistance and a cut- 80 out or circuit breaking switch in the direct current circuit advantageously in the line leading to and near the electrifier conduit; 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520

And advantageously, the said vessel consisting of a vacuum vessel on insulated supports and with the above combination; and with means of creating a vacuum in the vessel after placing the materials, the furs and the like therein, as with a suitable centrifugal or piston air pump or ejector and the like with piping connections for withdrawing air and moisture from the chamber of the vessel and the furs; with means of at- 70 temperating the vessel to a temperature not injurious to the furs and the like during the continuance of the vacuum and advantageously by well known electrical means under due control advantageously to a tempera- 75 ture not over about 100° F.; or attemperat- 80 ing similarly with hot or cold water in a surrounding attemperating jacket or coil or the like; with means for then connecting the vessel or the plate shelving thereof which 85 support the materials, with one pole of the above electrifier apparatus, advantageously the positive for furs, the other pole being earthed, during the continuance of the vac- 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520

And advantageously (with means to utilize the same vessel or analogous enlarged chamber for drying purposes to wit), with means of withdrawing all liquor from the chamber; means of exhausting moisture, vapor and air from the chamber and contents by vacuum producing apparatus as 110 above; means of passing hot drying air and the like into and out of the chamber; means of similarly passing ozone or oxygen or the like into and out of the chamber; all under insulated conditions.

Though I may adapt the electrifier apparatus to existing vessels, vats and the like, of metal now used in the art of dyeing, it is advantageous from the standpoint of economy of current supply, as well as for 120 delicate dye colors, to use vessels and vats of stoneware or china or a dielectric, excepting for the electrifier conduit tubes, plates and the like, and for the reason that a much larger quantity of current must be 125 provided to saturate the large amount of metal vessel, than where a dielectric vessel is used, and for which latter the smaller amount of metal plate or tray and the like which I provide is to be used as described 130

or analogous manner, electrically connected by wire with the D. C. supply, to electrify the materials by contact under insulated conditions. Other alternative steps of the 5 process and features of the apparatus are hereinafter recited.

I illustrate this process, apparatus and product specifically as applied to furs or dressed pelts, though it will be understood 10 that similar processes pertain to other materials to be dyed more especially animal fibers, *i. e.*, wool and silk and textiles thereof and animal products such as feathers.

By fur herein I mean more especially the 15 duly commercially prepared, cleansed and dressed dry pelt; and in some cases with what is known as the water or hard top-hairs removed, as with seal and beaver skins, though it will be understood that the 20 process is applicable also where the hard top hairs are not removed.

The fur, hair or fiber generally differs from the overhair, in that it is soft, silky, curly, downy, while the over-hair is 25 straight, smooth and comparatively rigid.

On living animals, the over-hair keeps fur hair filaments or fibers apart; therefore in many pelts for furs, such are retained; and where the removal is desired, such is advantageously done after the main dyeing. 30 Or I advantageously rely on the electrification of the hair to keep same apart. By fur, I include what is known as imitation fur as for instance where hare skins are dyed a sable color, to imitate sable; or nutria skin is dyed to represent seal skin, and the like. By fur herein, I also mean where the pelt has already been put through a degreasing operation, technically called 40 "killing" so that the individual fibers will be in a most fit condition to be electrified and to absorb the mordant and the dye liquors.

I attain my process by the means and 45 mechanism illustrated in the accompanying drawings in diagram, in which the same letters and numbers apply to analogous parts throughout the several views, and showing applications to old apparatus or structures, 50 to wit:

Figure 1 is a vertical section in diagram of an electrifier vacuum vessel with connecting pipes for creating vacuum therein and for circulating dye liquors there- 55 through; and with the application of the electrifier apparatus.

Fig. 2 is a diagram of symbols of the electrifier apparatus for application to vessel of Fig. 1 and other dyeing vessels.

60 Fig. 3 is a diagram in perspective of a metal tray for holding furs or pelts and the like, to be immersed in a dye-vat; and application of the electrifier apparatus to the tray.

65 Fig. 4 is a diagram of a metal comb and

the like with the application of the electrifier apparatus thereto for combing and electrifying a pelt or fur and the like.

Fig. 5 is a diagram of a plate for rubbing a fur pelt and the like thereon, with the 70 electrifier apparatus of Fig. 2 applied to the plate.

Fig. 1 is a vertical section in diagram of what I call an electrifier vacuum vessel V in which the materials to be dyed are subjected to and exhausted in a vacuum and then saturated with dye liquor therein. V is a closed vessel or pot or kier or the like; with a large front door, not shown, hermetically sealed when closed, with a series 75 of shelves, composed of plates P, arranged slightly inclined downward, of electrically conducting material, electrically connected together, and with means advantageously of sliding the plates on zinc racks separately in 80 and out of the vessel horizontally when door is open; the shelves spaced several inches apart on suitable racks, advantageously about 1 to 4 inches to admit of readily placing solid materials, furs and the like thereon 85 or advantageously placing baskets B or trays, Fig. 3, with furs on the shelves or plates.

P¹ is an entrance pipe for dye-liquors and the like fed from supply tank of dye-liquor 90 or funnel T, through way r¹ of a 3-way cock or three way manifold or the like; and entering top of vessel through insulator bushing I¹—and the liquor passing therefrom through nozzle or spray N¹ and falling upon plate P² advantageously convex, 95 electrically and mechanically removably affixed to pipe P¹ above the nozzle N¹; the plate P² may be perforated; plate P² does not touch sides of vessel there being about 100 an inch of space to permit liquor to flow over and fill the vessel. The pipe P¹ connects through way r² of 3-way cock L with circulation pipe P³ to way f¹ of 2-way cock L² thence to injector or vacuum pump K, 110 thence to P⁴ to bottom of vessel to 2-way cock L³, the injector K is connected through F² with pipe K² being inlet pipe for steam and its source not shown, or compressed air, or water jet and the like, for furs, and its 115 source not shown. Thereby a circulatory system for the liquor, etc., is provided, from bottom of vessel through P⁴ and P³ and P¹ to P².

The pipe P¹ also connects through way r³ 120 of the 3-way cock L to air or gas inlet pipe G from a suitable reservoir not shown.

In all pipes connecting with the piping of the circulating system for vessel V or the like, to wit, in pipe from supply tank T, 125 and in air or gas reservoir pipe G, and in pneumatic or steam supply, or the like, pipe K₂ and in exhaust pipe f² from K if it is connected with any condensing or other vessel not shown; and in drainage pipe O, if it 130

is connected with any other vessel; and likewise in any piping leading to and from the attemperating jacket J or the attemperating coils not shown or the attemperating can, I advantageously place a dielectric joint or section of piping D J; and with the object of further completely insulating the electrifier vessel and its circulatory system of apparatus whether for liquid or gas or air, during the application of the electrifier apparatus.

I advantageously use for fur dyeing, a circulating system such as indicated, a circulating syphon advantageously closed and operated with injector K operating with compressed air, *i. e.*, a pneumatic injector; or using air-jet lift, with or without compressed air; or the acid-egg or montejus system; or what is known as the automatic blow-case for lifting liquids by compressed air, or a water-jet exhauster; and the like.

Where the diluting and heating from small amount of condensed steam is not objectionable, as with wool or silk, I may use the steam injector system.

L¹ is a three-way manifold or 3-way cock in the circulatory system adjustable so that way r¹ opens passage way from T, the liquor supply tank, into the pipe P¹, and simultaneously cuts off the way r² from pipe P³ and the 3d way r³ leading to pipe G from hot air or other gas reservoir, not shown; conversely cock L' is adjustable to open r² from pipe P³ and simultaneously close way r¹ from T. And when cock L' is adjusted or turned to open 3d way it simultaneously closes r¹ and r² to permit the entrance of hot dry air, or other gas from its reservoir to and through P¹ into top of the vessel V, thence to outlet O at bottom if under pressure, or to injector or suction K thence to 2-way f² cock L² adjusted to close pipe P³ and open way f² to air free exhaust pipe 2 leading to waste pipe E or gas reservoir not shown or the like; and such is also the adjustment of L², with L' adjusted so as to be closed entirely to create a vacuum or near vacuum in vessel V. As a precaution for safety, an additional cut-off cock is inserted at D J in pipe P¹, there being also at D J a dielectric joint or section of pipe P¹, not shown. L³ is a two-way cock in P⁴ adjustable to open the way t¹ from P⁴ to bottom of vessel V simultaneously closing exit way t² to drain pipe O; and adjustable vice versa to open the latter and close the former in order to withdraw all liquor direct from vessel V. J is a well-known attemperating jacket or vertical coil not shown; around top, bottom and sides of vessel or all except the door with means such as pipes A, A², A³ of passing attemperating liquids cold or hot, or steam therethrough to attemperate the vessel, with a 2-way cock L⁴ to drain the liquids entirely therefrom or to pass

same to higher lever A₃, or in lieu thereof, I use a large cup J₂ with drain valve in which is placed at coil P₇ of an extension of pipe P₁ thus constituting it as part of the supply and circulating pipe system; and to 70 which the electrifier apparatus may be affixed; the cup is filled with cold or hot attemperating liquid, advantageously oil, which attemperates the passing dye-liquor.

By continuous liquid circulation, I include where such is attained, by hand power in lieu of injector of pump K, and omitting connecting pipes P₃ and P₄ and retaining O; as for instance, in some cases, in small establishments, I fill the vessel V by hand-buckets, pouring the dye-liquor therefrom into the funnel or tank T and allow it to percolate through the vessel and furs by gravity or with pressure from air pump; and withdraw the liquor from bottom pipe O into buckets; and thence again into funnel T; and separating the passage; and with the electrifier apparatus applied as above described. In such modifications, it is advantageous to attain as much gravity pressure as height of ceiling of room permits by using in lieu of coil P₇, a vertical pipe not shown, placed in attemperating high similar cup, not shown, with inlet and outlet pipe for hot or cold water and the like there-through, with funnel at top of vertical pipe; and omitting from the vessel the attemperating jacket J.

Fig. 1, the electrifier apparatus is shown in diagram with positive pole connected 100 with plates P per wire W from pole changer PC (shown after Fig. 2) from positive terminal of storage battery SB or other direct current supply, with negative terminal earthed through resistance or rheostat R, 105 and a similar electrifier apparatus shown analogously electrically affixed to supply pipe P¹ being clamped thereto at CE with wire W leading to pole changer PC adjusted to lead to negative terminal of storage battery SB whose positive terminal is shown electrically connected to ground through resistance or rheostat R, or I may detach the clamp CE of electrifier apparatus from plates P and attach the clamp at CE 110 of pipe P¹ and change the P C to connect the negative pole to P¹ and the positive to ground; the latter being advantageously done after the vessel V is filled with dye-liquor.

At I, I, are shown insulator supports, there being other similar insulators not shown, supporting the vessel V and all connecting pipes, tanks and machinery.

Fig. 2 is a diagram of symbols of the 125 electrifier apparatus proper, adaptable for the electrification purposes stated, when applied to and in combination with old structures, dyeing vessels and the like or with improved vessels or appurtenances there- 130

for as shown symbolically in Figs. 1 and 3 and 4 and 5.

In Fig. 2, SB represents any direct current supply, which may be a storage battery, 5 or d. c. dynamo; or a constant current generator (as per symbol at DCG in Fig. 3), or a d. c., duly converted from A. C. source, or an influence machine or frictional machine, or a primary battery of cells or other 10 direct current supply advantageously constant, with well-known means not shown of increasing or decreasing the supply to attain suitable high or low voltage and amperage with continuous supply, to be determined empirically for different materials, 15 different kinds and conditions of furs and different colors, dyes and the like. P C represents a pole changer switch connected with the terminals of the D C supply S B, 20 with a separate insulated wire W' to earth C G; and with circuit breaker switch s, and advantageously with voltmeter, ammeter and resistance or rheostat R advantageously in the non-grounded terminal line W in 25 series therein, and a suitable detachable clamp C E at its end, to be clamped or fastened to electrifier plate P or electrifier conduit P¹ of Fig. 1, or to electrifier tray of Fig. 3, or electrifier comb of Fig. 4 or electrifier plate of Fig. 5 or the like; and which 30 I call the extension of the terminal. It will be understood that in lieu of such detachable clamp, an equivalent attachment can be used such as soldering or brazing the wire there- 35 to. The manually operated circuit-breaker switch S is shown as being open; it may be placed anywhere in the circuit; when closed the P C is shown as being connected to lead the negative pole to earth and the positive 40 pole to P. When the P C is thrown to the right so as to rest upon or connect with buttons 2 and 1 in lieu of 3 and 2 as shown, then the positive pole is automatically thereby connected to earth and the negative to P. 45 It will be understood that a voltmeter, and ammeter and rheostat or the like are advantageously used in the non-grounded terminal line W as shown in Fig. 3; though such may be in line to earth. It will be understood 50 that the pole changer switch may be dispensed with and the terminals of the d. c. supply connected direct, the one to earth and the other to the electrifier plate, tube, conduit, vessel and the like, by well known 55 means, and substantially as described. By the term d. c. supply or circuit, I mean a metallic circuit or the like of which the earth forms no part, excepting as herein described.

Bearing in mind ohms low

$$60 \quad C = \frac{E}{R}; \text{ or } R = \frac{E}{C}$$

and also that the passage of a current through a resistance R is attended by a fall 65 of potential proportional to R, I advanta-

geously use a rheostat to increase resistance accordingly, and to thereby increase difference of potential between the electrifier plate and the d. c. supply source *i. e.* in addition to resistance of the circuit line and 70 source; and advantageously by resistance in the line near the contact plate or conduit or the like, or by making the contact plate of resistor material; and also considering the heat resulting by a resistor in the line, 75 and which in some cases may be objectionable and in others may be an advantage or not objectionable; in the latter case the contact plate or conduit is advantageously made of a poor conductor or resistor which 80 would act as resistance; and where heat is a disadvantage as with some furs the contact plate is made advantageously of superior conductor material, and the additional resistance or the rheostat is used elsewhere 85 in the circuit, advantageously in the non-grounded terminal line near the clamp affixed to electrifier plate.

Though I may use as the material for making the contact electrifier plates or conduits or trays and the like, any conductor material, advantageously acid-proof and non-oxidizable, yet when the principal use therefor is to confer positive electrification, as for furs, I advantageously use pure iron 90 or steel; and where the principal use is to confer negative electrification I advantageously use copper or silver or nickel or lead or zinc, or an alkali alloy or oxids of metals. 100

Where the heat resulting is not sufficient to constitute a disadvantage as in dye-liquors before the immersion of furs therein (and which liquors are cooled before the immersion) but not in the electrifier plates 105 for furs, I advantageously make the electrifier contact portions of a resistor material such as German-silver, or copper, or manganese, or copper nickel, or nickel-steel or nickel chromium alloy and the like; and 110 the connecting wires of a superior conductor; and likewise in the electrifier conduits for sundry dye-liquors, I advantageously use a section or joint of pipe or conduit made of such resistor material, the remainder or connecting conduit being of superior 115 conductor material.

I advantageously use for liquids, resistance of 24 ohms upward for negative and 48 ohms upward for positive electrifications. 120

I advantageously use for dry furs, down, etc., about 100 V upward and 50 amperes with a resistance of about two ohms upward. 125

In the process for furs, or where low temperatures are material, I advantageously construct the electrifier contact plate or conduit for use as resistance like a thermo-electric couple or pile in lieu of a homoge- 130

neous metal resistor to attain the Peltier and Thomson effect; with the electric current forced across the junction of the metals of the pile connected in series in the 5 d. c. circuit with the current flowing in the same direction as the thermo-electric current flows at the hot junction; thereby the junction will be cooled.

The dye-liquor, prepared substantially as 10 at present, is always cooled for use in my process for immersion of furs advantageously to about 80° F. before immersing the fur; and in electrification of such liquors, as herein described negatively, I 15 advantageously use a current of about 1200 V. upward; and generally at least about 50 V more and advantageously double or 2400 V for positive electrification. For such, I provide amperage of about ten amperes or 20 more per square foot of the contact surface of the electrifier conduit or plate; or sufficient amperage to attain an electrostatic charge of about one millionth of an ampere upon an ion or molecule or particle 25 of the material being treated; advantageously empirically determined with different materials. I advantageously use a contact pressure of two pounds upward per square inch and a velocity of about one inch per 30 second upward. The electrically adsorbed component of any dye-stuff and the like or of compounds of dyestuff with mordants and the like precipitated from the solutions are fixed and adsorbed by the solid materials, *i. e.*, in furs in both skin and hairs 35 with an enhanced density, by and due to the electric forces with the result that the enhanced density increases stability, and durability and diminished hygroscopicity; and 40 with increased resistance to detachment of the adsorbed atoms, molecules and particles upon exposure to moisture, light, heat and ordinary wear and tear. And this effect pertains largely both to the skin and to the 45 furs or feathers of a down and the like, where the dyeing is by submersion in the dye liquor of the whole pelt or down and the like; and thereby a desired similarity of color in both skin and hair is attained.

50 In the conduct of this process with the said electrifier vacuum apparatus, Fig. 1 and electrifier apparatus Fig. 2, I proceed as set forth in describing said Figs. 1 and 2 as follows:—The dressed dry fur is placed 55 with fur side down on plates P, or in trays B which are placed on plates P or trays B may be stacked one above the other, in the chamber of vessel V; and the wire w from electrifier apparatus of Fig. 2 is electrified 60 connected with P or B; and the pole changer P C adjusted to lead the positive terminal of the d. c. supply to P or B and the negative to earth; the cut-out switch S is then closed; the door of vessel V is then 65 closed; the 3-way cock L' is turned so as to

close all ways; cock L₂ is turned to close the way f¹ pipe P³ and to open the exhaust way f² from injector K. Cock L₃ is turned adjusted to cut off pipe O and to open the way from bottom of vessel to pipe P₄ to injector or vacuum pump K; the vacuum creating injector or pump is then duly operated for a few minutes, to subject the material to and to exhaust same in as near a vacuum as practicable. It will be understood that an entirely separate vacuum creating apparatus of well known type may be used, to create vacuum in the vessel V as an alternative to the means described. A vacuum gage, not shown, affixed to vessel 70 will indicate the stage of the vacuum; the vacuum creating apparatus is kept in operation until the gage indicates advantageously over 25 inches of vacuum pressure. 75

The vacuum in vessel V is continued several minutes, advantageously over five minutes, not only to exhaust air, but to exhaust and to allow the fur, hair or fiber to open out,—that is, so that the scales or the like, of the hair which are closely adherent to 90 the shaft of the hair, may be freed from air pressure and thereby the edges assisted toward turning outward from the shaft, to allow of more ready penetration of the dye-liquor. The time therefore and voltage and 95 amperage will vary with different furs, to be determined empirically. Thereby the furs are electrified positive. The vacuum creating pump or system is then cut off. Thereafter the 3-way cock L' is adjusted to 100 close all its ways except way r₁ and cock I₆ is opened to permit inflow of dye-liquor from its reservoir or funnel T, to fill the vessel V with dye-liquor through attempting coil P⁷ and Pipe P' and nozzle N¹; and 105 cock L₂ is adjusted simultaneously to close its exhaust way f₂ and open f₁; and simultaneously the electrifier apparatus of Fig. 2, *i. e.*, a separate set thereof P C₂ is electrically connected at CE₂ with inlet pipe P' connecting its negative pole therewith, and with its positive terminal earthed, to electrify the passing dye-liquors advantageously, 110 negative, *i. e.*, with sign opposite to that of the plates B and furs thereon; and with higher voltage and amperage, advantageously as above stated. And thereafter as the vessel is filled, and during the circulation of the dye-liquor hereinafter described, the pole changer switch P C₁ is 115 turned so as to connect its negative with the plates P its positive being earthed. In other words, during the subsequent operating of the liquor circulatory system after the first filling of the vessel, all plates and inlet piping 120 are electrified alike. Thereafter the vessel V being full, cock L₆ is closed cutting off the supply of dye-liquor from tank T; and 3-way cock L' adjusted to open the way r² from pipe P₃ to coil P₇ and pipe P¹; and 2-way 125

130

cock L_2 adjusted to close its exhaust for air-way f^2 and to open its way f^1 from injector K ; and 3-way cock L_3 is adjusted to open l^2 from P^4 and l^1 to bottom of V , closing out 5 let O ; and then operate the injector K by well known means not shown such as compressed air above indicated; thereby or by other equivalent known means not shown, setting up a continuous circulation of the 10 dye-liquor from bottom of vessel through circulating pipes P^4 and P^3 and P^1 to top of vessel and downward permeating the fur to bottom, and repeating such circulation. Such circulation is repeated advantageously 15 intermittently by cutting off the injector action intermittently for a few minutes at a time to allow the dye-liquor to permeate and saturate the fur more thoroughly; and such circulation is kept up 20 or repeated advantageously for half an hour or more, varying with different fur, to be determined empirically. I regulate the temperature to any desired point, noting the thermometer t and using attemperating 25 liquids in jacket J , or in the cup J_2 in which is a coil of conduit pipe P^7 leading to P^1 . Thereafter the injector K action or the like is stopped and all dye-liquor withdrawn from the exhaust bottom pipe O by opening 30 its outlet cock, L^3 closing its way l^2 ; thereafter the door of vessel V is opened and the trays of furs taken out and the furs duly dried and the dyeing thereupon conducted and completed as at present. 35 And advantageously in lieu of present drying methods I may use the vessel V as a dryer as follows: after emptying the vessel of all liquor, I advantageously take out the furs or trays B with the furs, and place 40 same in well-known centrifugal machines not shown, to thereby centrifugally remove as much as possible of the remaining liquor and moisture clinging to the fur and hide; and use any other known dryer systems. 45 After centrifuging, in some cases, it is advantageous to stretch the fur, hair side down flat on a table or on flat trays and clamp it down; and cover with half inch mixture of drying meal as at present, such as equal 50 weights of alum and common dry salt and a dry meal; or to revolve loose moist skins with such meal in a revolving drum, as at present, until dry; and thereafter replace the trays and furs in the vessel and hermetically 55 close the same; and proceed with the drying at a low temperature advantageously about 70° to 98° F as follows: The 3-way cock L' is adjusted to close way r^1 from supply tank T , and open way r_3 to pipe G which 60 connects with a reservoir not shown, of dry warm pure air of about 70 to 100° F., with means, not shown, of forcing or sucking same into and through the vessel, circulating through the fur with exit at bottom 65 through O ; or advantageously utilizing the above described vacuum creating apparatus to suck and draw the dry warm air from said way r_3 and pipe G reservoir, into and through the vessel V and its furs, and out through L_2 way f_2 to waste or 70 condenser or other vessel. In lieu of a reservoir (connecting with G) of warm dry air warmed and dried and purified by well known means, I may use ordinary atmospheric air thus sucked in and 75 warmed by passage through J_2 coil immersed in water to heat it to about 70 to 100° F. and in cases where air is now used to oxidize or further oxidize the dyestuff or dyed fur, I advantageously use and similarly apply from such reservoir through pipe G ionized air or ozone on an oxidizing gas, while simultaneously applying the electrifier apparatus, advantageously negative to pipe P_1 to further electrify the gas, 80 air or ozone negative and intermittently stopping such to apply positive to fur plate P to electrify the fur positive; and then renew the circulation of the negative gas. And in some cases I may use the circulating 85 continuous system the same for the drying air or gas as described for circulating liquids. And in lieu of thus drying and oxidizing in the vessel V , I utilize similarly any existing separate drying room or chamber 90 by duly insulating it, hermetically sealing it, and suspending the furs therein as at present; or advantageously in trays for electrifying the furs as described for Fig. 3, with same means for electrifying the trays; and 95 with inlet and outlet piping for warm dry air for said drying chamber as at present adopted, or in lieu of atmospheric air, to use ionized and electrified air or ozone as above described. 100 It will be understood that I may conduct the same process without the vacuum in the above vessel V Fig. 1 or in what is known as the injector kier now used in bleaching and in dyeing operations; and analogous 110 vessels and I so do by supporting same and appurtenances on insulators and placing therein a like system of electrifier plates and likewise electrically connecting such with the electrifier apparatus of Fig. 2, and conducting the process with such as described. It will be understood that in lieu of using a vacuum vessel such as V Fig. 1, with the circulatory system above described, I may use 115 in my process any vacuum vessel without such circulatory system or the like; as for instance, by electrifying the furs placed on trays as described for Fig. 3, and then placing such trays and furs in a vacuum vessel, and upon closing such exhausting the air 120 therefrom; and thereafter fill the vacuum vessel with dye liquor, advantageously using the air-exhaust pipe entering at top, with a 2-way cock to introduce the dye-liquor by gravity. Or, as an alternative, vice versa, 125 130

by electrifying the dye-liquor only, negative, and similarly introducing such into the vacuum vessel after placing the furs therein and after exhausting the air. Or alternatively first electrifying both fur and dye liquor, separately, and with opposite signs as described in connection with Fig. 3, and then proceeding as above, *i. e.*, place the trays and furs electrified in the vacuum vessel or 10 on shelves in the vacuum vessel;—close the latter;—exhaust the air;—and then introduce the dye liquor as above;—and withdraw the liquor from the bottom outlet pipe; and after repeating such immersion as 15 often as may be found empirically necessary, further conduct and complete the dyeing as at present. The immersion of a fur pelt, or a down and the like, in the dye liquor subjects the skin likewise thereto; the high 20 temperature of ordinary dyeing would injure the skin by dissolving some gelatins thereof, and which I avoid by keeping the temperature of the dye-bath liquor low or under 100° F. Such restriction or low temperature is not essential in the “top-dyeing” hereinafter described,—due care being 25 taken therein not to allow the hot dye liquor to touch the skin of the fur or down and the like.

30 The conduct of the process is further advantageously simply described in connection with Fig. 3 which is a diagram of a perspective isometric view of a wire basket or metal tray B, with numerous perforations, advantageously with clamps or fasteners F to hold furs in suitable place, in the tray, and which has rubber covered or other dielectric handles H, for grasping the tray under insulated conditions, when to be placed on 35 plate P of Fig. 1; or for placing the tray and fur on any present dye-bath tub or vat like V' Fig. 3 for soaking in the dye-liquor therein, as at present, but previously the tray and the dry dressed fur in contact 40 therewith is placed on insulator supports I, I, advantageously upon and in the bottom of vat V', and electrically connected prior to the immersion with the electrifier apparatus similar to Fig. 2 as shown in Fig. 3 with 45 a d. c. generator D C G in lieu of a storage battery; advantageously with the positive pole for fur, and the negative earthed; the fur being placed advantageously with hair side down, resting on the tray; and 50 after a few minutes electrical contact, the entire tray is lifted by the insulated handles and immersed in the dye-liquor or in present vessel or tub V supported on insulators I, otherwise thereupon the dyeing 55 process is conducted and completed as at present.

In lieu of the tray form of Fig. 3, as an alternative, I use a hollow plate, not shown, like a water cooled electrode with its cool-

ing appurtenances not shown to attemper- 65 ate same advantageously to 80 to 100° F.

As an advantageous alternative to the latter or present dye-liquor bath step the dye-liquor in its insulated tub or vessel V' is first advantageously electrified with sign 70 opposite to the above dry fur, by immersing and agitating therein under insulated conditions a metal terminal such as the said empty metal tray electrically connected with the opposite pole, advantageously negative for 75 fur dyeing, of the electrifier apparatus of Fig. 2, the positive being earthed; the tray thus electrically connected by wire is grasped at its insulator handles H advantageously by suitable insulator tongs, not 80 shown, or by the rubber gloved hands of the operator, and is immersed and plunged up and down repeatedly in the dye-liquor for about five minutes or more; and thereafter another previously oppositely electrified tray holding the fur is immersed in the dye-liquor similarly *i. e.*, by grasping its insulated handles H in similar manner and immersing it under insulated conditions. Thereupon electrical adsorption and 85 reaction and compounding is accelerated and effected of the dyestuffs or components thereof, upon and in the fur due to the opposite electrifications thereof, otherwise the dyeing is conducted and completed substantially as at present.

In Fig. 2 C E represents any well known form of a detachable clamp for firmly electrically connecting the wire W of the electrifier apparatus of Fig. 2 to the metal tray or wire basket and the like of Fig. 3 to hold a fur and the like; such clamp C E not shown in Fig. 3 be part of end of wire W or may be part of tray B; F, F, represent detachable fasteners advantageously 2 or 4 and on opposite sides of the tray, to fasten or clamp the hide edges of the fur, so as to hold the fur in the tray advantageously with hair side down before immersion, and to hold the hide side of the fur at a suitable height from the bottom of the tray so that the tips of the fur hairs will be in touch with the bottom of the tray; the height of the tray is advantageously slightly higher than said height, about quarter inch, so that a number of trays can be set on each other, slightly zig-zag and supporting each other, in the dye-vat, and thereby an upper tray will not compress a fur in a lower tray which compression would impede a ready ingress of the dye-liquor among the hairs. After the immersion the pelt may be placed in tray with fur side up. Fur pelts from different animals have different length of hairs; it is advantageous to have different heights and sizes of trays accordingly.

Fig. 4 is a diagram of a metal comb P₅ or the like, electrically connected with the

electrifier apparatus of Fig. 2; the wire W is sufficiently long to permit moving the comb P₅ by an insulator handle or with the rubber gloved hand or the like, through the fur or a pelt, or the wool of a sheep-skin and the like placed on an insulator table or support not shown; or placed with fur side upward on a table or tray advantageously of dielectric material. Such comb is advantageously a strip of metal with one edge indented so as to form a series of teeth, or several of such strips, set parallel to one another in a metal frame as in a curry comb; or like a card used in a hand carding or in a carding machine for separating and dressing wool; the length of the teeth being advantageously the length of the hair of the fur or wool of a sheep-skin and the like means of attemperating such comb advantageously to 80 to 100° F. during the combing are advantageously provided, as by circulating a stream of water through its back J' made hollow and with appurtenances not shown, like a water-cooled electrode; or advantageously often dipping the solid comb in a cold water bath and then drying and then continuing the combing.

In the operation of the process with such electrifier comb P₅ and electrifier apparatus, the fur pelt or the like is placed on insulator supports as indicated; and the comb drawn through the fur advantageously by the insulated hand or by insulator handle or using carding machines with insulated combs, or the like.

Thereafter the dyeing is conducted under insulated conditions as above described with use of trays like Fig. 3 advantageously of dielectric material, the electrified pelts being placed therein under insulated conditions, that is, with the rubber-gloved hands and the like, the trays being supported on insulators. Otherwise, the dyeing is conducted and completed as at present.

Fig. 5 illustrates in diagram a vertical section of a curved metal plate P₆ advantageously a semi-cylinder, circular or ellipsoidal in cross section, and advantageously a flattened hollow J₂ metal pipe, with water circulating therethrough like a water-cooled electrode with its attemperating appurtenances, not shown, to maintain its temperature at 80 to 100° F.; and which can be alternatively attained by dipping periodically in cold water and drying; and supported on insulators I, I; and electrically connected advantageously at under side with wire W of the electrifier apparatus of Fig. 2; the upper contact surface of such plate may be comb-like, analogous to a curry comb or with many furrows cut thereon or the like. In the conduct of my process therewith, I electrify the fur thereon, advantageously by grasping the two ends Y of the pelt, with rubber-gloved hands, not shown; or the

equivalent mechanism, *i. e.*, for rubbing the fur upon and over the said contact surface; as by clamping insulated arms of a to and fro moving mechanism of a machine not shown; and with the fur side *w* of the pelt downward and pressed gently against the plate P₆ duly previously electrically connected with the wire *w* of the electrifier apparatus, and with the pole changer adjusted to connect with one pole, advantageously the positive for furs, the other pole being earthed, upon closing the switch S; the belt is then passed to and fro with the tips of the fur in contact with top of plate for a few minutes and after such electrification of the fur, the pelt is placed as aforesaid under insulated conditions in trays or otherwise in the dye-bath; and the dyeing proceeds as above described for Fig. 4.

In the conduct of the process, in some cases, and in what is known as "top-dyeing" or "blending" in lieu of immersing the fur in the dye-liquor in a vessel as above described, I conduct the dyeing, after electrifying advantageously positive, the fur as above described, by brushing or spraying and the like the dye-liquor on the fur advantageously under insulated conditions, *i. e.*, supporting the electrified fur, or the above tray holding the fur, on dielectric supports; and then brushing the dye-liquor on the fur as at present in top-dyeing and the like but with an insulated brush, one whose handle is advantageously covered with a dielectric; and thereafter allowed to stand until dried; or advantageously dried in a suitable drying room or drying method as at present; or in a stream of drying air and the like as above described. The dye liquor for brushing may be either neutral, or prior to its use for brushing as above described, may advantageously be electrified as above described with a sign advantageously negative or opposite to the fur. Otherwise the dyeing is conducted and completed as at present.

In some cases of dyeing of an imitation fur, as of inferior skins to produce thereon the markings of a natural fur, the suitable dye liquor now used is brushed upon or sprayed upon the electrified fur or vice versa, as above described, in as close imitation of the genuine article as possible, and then conducting the dyeing as above and otherwise completing the dyeing as at present.

It will be understood that, as in the past, or present methods, all fur skins dipped in various dyestuff solutions must be again softened after drying. And in some cases, a regular retanning like the original tanning, may be necessary; but usually a damping, staking and oiling as at present of the leather or skin side is found sufficient, es-

130

pecially in my process where the dyeing is at low temperature under 100° F. And even such is unnecessary, when dye is brushed on the hair as in top-dyeing above described, and when the skin proper is not affected.

The duration of the immersion may be as at present—but advantageously much less time to be determined empirically for 10 different dyes and kind and condition of furs.

Ordinary dyestuffs marketed for coloring textiles must be applied to textiles at high temperature—in many cases boiling hot.

15 Such are inapplicable for furs as the skins would become partially dissolved thereby. But some such can be used for top dyeing. Sheepskins are sometimes now dyed with these colors by fastening them on boards or 20 frames and allowing the wool alone to come in direct contact with the hot dye liquor. I likewise adapt my process as in brushing above described.

Some varieties of fur pelts have wiry 25 bristly hairs which will be duly treated, *i. e.*, "killed" as at present prior to applying my process.

Furs are now largely dyed by the oxidation of coal-tar dyes on the fiber; principally 30 by the oxidation on the fiber of the base paraphenylenediamin or para-amido phenol, or ortho amido phenol; pyrogallic acid is used to a less extent. This is carried out ordinarily by first mordanting the 35 fur with an oxidizing agent, principally bichrome or copper sulfate or iron salts. Light shades are dyed without previous mordanting but dark shades are first usually mordanted.

40 Hydrogen peroxid is the oxidizing agent ordinarily used in the dye-bath or dye-liquor and is added to the dye-liquor in the bath after the fur hair has become thoroughly saturated with the base; but in 45 some cases the hydrogen peroxid is added to the dye-liquor before its use; one such latter formula for black dye is as follows: 5 pounds paraphenylenediamin dissolved in boiling water; then made up to 7½ gallons with cold water; made slightly acid with acetic acid; cool and add 2½ gallons hydrogen peroxid (10 volumes). For dyeing brown the same formula is used except that the liquor is made slightly alkaline 55 with soda ash, in lieu of acid with acetic acid. For a brushing dye-liquor on an imitation or inferior fur to imitate the markings of a superior natural fur, a solution of one of the above bases mixed with hydrogen sulfid may be brushed on the former, 60 as above described.

Another formula for black dye liquor is as follows: Make a 1% solution of paraphenylenediamin in pure water; make it 65 slightly acid with acetic acid. Immerse

the furs therein as above described at a temperature under 98° F. until thoroughly saturated; and then add 5 c. c. hydrogen peroxid (10 volumes) for every gram of paraphenylenediamin and allowing the 70 bath to fall to normal temperature. With present processes 8 to 10 hours immersion is required to develop a full black on the fur, the bath being kept acid; but with my improved process, far less time is required, 75 depending on the fur and to be determined empirically; as a general rule less than one half the time and less than one tenth the time where the vacuum chamber above described is used.

80 It will be understood by the term dyeing herein described, I include mordanting where mordanting is first now advantageously employed, I use my process as described in the mordanting, *i. e.*, I conduct the process as described first with mordant liquor alone and thereafter apply the dye-liquor proper as at present; and such is advantageously done in dyeing furs, *i. e.*, first electrically mordant the fur. However, the 90 dye-stuffs may be simultaneously applied with the mordant in the same dyeing liquor, in the method described; and in some cases, the dye-stuffs liquor may be first applied and then separately the mordant solution. 95

It will be understood that by dyeing, I include "mordanting" with a mordant as well as dyeing with the color proper separately; also where such mordants and colors are applied in the one dye liquor, after 100 duly cooling the liquors both mordant and coloring liquors for immersion of furs, to 80 to 100° F.

Where the mordanting is first applied, it will be advantageous with furs as with silk and wool after the immersion in the mordant to advantageously follow with washing with water; then drying and electrifying and then use the dye-liquor for coloring.

105 Fur is advantageously electrified positive; therefore in fur dyeing I advantageously electrify the fur positive, and the dye liquor negative comparatively; or leave either, electrically neutral; and then bring same into contact as described. But it will be understood I may reverse the said electrifications. It is advantageous to use the more concentrated solutions of dyestuffs and in very pure water. Ordinary dyeing processes as regards temperature are inapplicable for 110 furs as such are very sensitive to heat; and in order to preserve the pelt, fur dyeing is conducted, advantageously, in the cold or at normal temperature; my process as described permits thereof; I advantageously 115 use dye-baths for animal fibers and furs at or under 100° F. or body temperature. It is advantageous to start the dyeing tepid or luke warm and raise gradually to 98 or at most to 120° F. and dye at this temperature 120

125 130

advantageously about half hour or less to be determined empirically for different weights of different animal pelts. At low temperatures it is difficult to insure the penetration 5 of some mordants and dye-stuffs and in such cases the vacuum feature herein described is advantageous, especially with furs where low temperatures are most desirable; and thereby sundry dyes not now applicable to 10 furs may be used. I also apply my process similarly to "down," i. e., the under-plumage of birds, swan, duck and other water-fowl; and to sundry feathers. Such are animal 15 productions in the category with fur. Wool and silk may be dyed at high temperatures 167 to 176° F. as at present and in full shades, but boiling heat is ordinarily used for dark colors; boiling heat is used to open the pores of feathers to allow full 20 ingress to interior by mordant and dye; but such high and boiling heat is injurious for pelts and down and is avoided by my process. While china or porcelain vats, 25 basins or vessels are advantageous for delicate colors, copper vessels with double bottom for heating are advantageous for black and dark colors. Large ostrich feathers are 30 advantageously dyed in a metal tray or sieve by my process as above described for furs, advantageously using the acid coal tar dyes and dipping the electrified trays with feathers, down, etc., therein under insulated conditions.

I do not restrict the process to mere dyeing, but likewise apply the same in sundry 35 well known bleaching operations of fibers, and textiles as well as furs and feathers and hairs, and the like; and in stripping colors therefrom. I do not restrict the process to 40 dyeing merely of furs and fur pelts and animal products but also to textile fibers and textile fabrics; and manufactures of straw, straw braid and the like; and to feather dyeing; and leather dyeing.

45 It will be understood that after the dyeing is completed with this process, the furs and the like, will be thoroughly rinsed, as at present, and in some cases advantageously "drummed" with absorbents, such as hard- 50 wood, sawdust, meal, etc., to dry and remove any loose coloring matter, and the like.

I claim:

55 1. An electric treatment in the process of dyeing dressed furs, down, feathers, hair, fibers, and the like, which consists in electrifying the duly dried materials to be dyed with one sign only, and separately electrifying the dye-liquor, with opposite sign, 60 and with different potentials, and then bringing the materials and liquor into contact; all under insulated conditions; and thereafter conducting and completing the dyeing.

65 2. An electric treatment in the process

of dyeing dressed furs, down, feathers, hair, fibers and the like, which consists in electrifying the dye-liquor with one electric sign only; and thereafter bringing same into contact with the material to be dyed; all 70 under insulated conditions, and thereafter conducting and completing the dyeing.

3. An electric treatment in the process of dyeing dressed furs, down, feathers, hair, fibers and the like, which consists in electrifying the duly dried material to be dyed with one electric sign, and thereafter bringing same into contact with the dye-liquor; all under insulated conditions; and thereafter conducting and completing the dyeing. 75

4. An electric treatment in the process of dyeing and the like, which consists in subjecting to and exhausting in a near vacuum, the materials duly dried which are to be dyed and then electrifying the materials with one sign only in the vacuum; and then bringing the dye-liquor electrified with the opposite sign and different potential, into contact with the materials in the vacuum; all under insulated conditions; and thereafter conducting and completing the dyeing. 80

5. An electric treatment in dyeing, and the like, which consists in subjecting to and exhausting in a near vacuum, the duly dried materials to be dyed and then electrifying 95 the dye-liquor with opposite sign; and then bringing the electrified dye-liquor into contact with the materials in the vacuum; all under insulated conditions; and thereafter conducting and completing the dyeing.

6. An electric treatment in dyeing and the like, which consists in subjecting to and in a near vacuum, the duly dried materials to be dyed; and then in said vacuum, bring into contact with the materials, the dye-liquor previously electrified with one sign only; and then continue and repeat the contact of the electrified dye-liquor and the materials without the vacuum; all under insulated conditions, and thereafter conduct 100 and complete the dyeing. 105

7. An electric treatment in fur dyeing and the like which consists in electrifying the duly dried and dressed fur pelt with one sign only; and applying the dye liquors 115 as at present with addition of insulated conditions; and thereafter conducting and completing the dyeing.

8. The process of electrifying with one sign only a fur and other fiber and the like which consists in bringing same in dry state under insulated conditions into physical contact with a conductor extension of one terminal of a direct current supply of a suitable voltage and amperage, the other 120 terminal being earthed, and with a suitable increased difference of potential between the electric source and said extension contact; all under insulated conditions. 125

9. The process of increasing electrifica- 130

tion of a material with one sign only by contact thereof, with an electric current circuit with one pole grounded, under insulated conditions which consists in increasing 5 the difference of potential between the electric source and the contact points and the like, over that due to resistance of the original circuit and the source.

10. The process of increasing the electrification of a material with one sign only, by contact thereof with an electric current circuit which consists in enlarging the size and shape of the non-grounded lead line of the circuit into a conductor conduit plate and the like 15 for said contacting and simultaneously grounding the opposite sign and keeping the current constantly supplied; all under insulated conditions.

11. The process of electrifying a fur and the like material with one sign only, which consists in bringing same in suitable form and under insulated conditions, into contact with a conductor conduit plate and the like which is in series in a direct current circuit 25 having its pole of the sign opposite to the above grounded, and of a suitable high voltage and amperage; and with an increased difference of potential between the electric source of supply and the said contact plate and the like, over and above such due to resistance of the circuit and of the source.

12. A dyed material with electrically adsorbed components of dyestuffs and electrical reactions of components from dyestuffs and mordants homogeneously fixed in and upon the fibers in nonstrained equilibrium of increased density and increased stability, and durability and diminished hygroscopicity.

13. A dyed material with electrically adsorbed components of dye-stuffs and electric reaction components from dyestuffs homogeneously fixed in and upon the fibers, of increased density stability and durability against deterioration from light, heat, moisture and time.

14. A dyed fur, and the like animal product having in and on its fibers, electrically adsorbed components of dyestuff and electrical-reaction compounds of components of dyestuffs, and mordants and the like, of enhanced density stability and enhanced durability of color and gloss as regards light 55 heat, moisture and time deterioration.

15. A dyed fur and the like animal product including a down, feathers, hair and fiber, having electrically adsorbed and electrically fixed components of dye-stuffs therein and thereon of enhanced stability, density and durability of color and gloss and with diminished hygroscopicity.

16. A dyed fur, and the like including a down and manufacture thereof having thereon and therein exclusive of the skin, electri-

cally adsorbed and electrically fixed compounds of dyestuffs of enhanced density and durability.

17. A dyed fur and the like including a down, having electrically adsorbed and compounded dye-stuff colors fixed in and upon the skin thereof and upon the fibers of the fur proper, hair, feathers and the like, the dye colors having enhanced density and durability and uniformity.

18. An apparatus of the nature described comprising a vessel suitable for the purpose stated, with insulator supports, with means of opening and hermetically sealing the chamber thereof, with supporting plates and the like, in the chamber, holding solid materials furs, down and the like to be treated; with means of creating a near vacuum in the chamber through suitable exhaust pipes connected therewith; with means of electrifying the plates and the materials in contact therewith, with one sign only by electrical connection with one pole of a direct current supply of a suitable voltage and amperage, the other pole being earthed, and with a voltmeter, ammeter, rheostat polechanger and cut-out switch, in the circuit of said d. c. supply; with means of forcing into through and out of said chamber and permeating said materials therein, suitable liquids, fluids, gases and the like by means of suitable circulation pipes; with means of attemperating the said liquids and the like; with means of repeating the said circulation intermittently and continuously through said circulation pipes; and with a dielectric joint at points in the supply and drainage and withdrawal pipes, connecting with the circulation pipes beyond and not in the circulating system with means like above electrifying means, of electrifying the circulation pipes during the said circulation with one sign only as desired; all under insulated conditions.

19. An apparatus of the nature described comprising a vessel for the purpose intended; with insulator supports thereof; with means of opening and hermetically sealing a doorway into the chamber thereof; with means of placing and withdrawing the materials to be treated, on plates, trays and the like, in said chamber, and insulated therefrom; with a supply funnel and the like and inlet connecting supply pipe and cutoff cock leading into top of said vessel and drainage pipe and cock from bottom of said vessel; with means of attemperating the same and contents; with means of electrifying the supply pipe and the plates intermittently of and with one sign only, for the electrification of the said pipe opposite to and with different potential for the sign of the electrification of the said plates, from a direct current supply of suitable voltage and amperage, the other pole being earthed;

- and with means of charging the pole; and with pole-changer, cutout switch voltmeter, ammeter and rheostat in the d. c. supply circuit; all under insulated conditions.
- 5 20. In an apparatus of the nature described, the chamber of a vessel on insulator supports; with means of ingress and egress and of hermetically sealing same; with means of placing thereon materials to be treated with means of forcing liquids and fluids in to and through the said chamber, through piping connected therewith, with means of electrifying said piping by electrical connection with one pole of a direct current supply and other pole being earthed; with means of attemperating the said piping; all under insulated conditions. 70
- 10 21. In an apparatus of the nature described, a drying chamber of a vessel on insulator supports, with means of duly placing materials to be dried therein with means of electrifying the materials therein with one sign only from a d. c. supply with means of forcing ionized air, gases and the like, electrified with one sign only, being the opposite to the aforesaid, into and through and out of the said chamber; all under insulated conditions. 75
- 15 22. An electrifier apparatus in combination with a vessel and conduits and the like of the nature described, comprising a direct current supply circuit with means of controlling the supply; with pole changer switch in the circuit with means of earthing from the pole changer one pole of the electric supply, and means of electrically connecting the other pole to and with a conductor plate, pipe, tube, conduit and the like in contact with material to be electrified, with means of attemperating the plate and material; with cut-out switch, voltmeter, ammeter and rheostat in the said circuit all on insulator supports. 80
- 20 23. An electrifier apparatus of the nature described comprising a direct current supply; with means of controlling the supply; with means of earthing one pole thereof and with means of electrically connecting the other pole to a conducting plate, pipe, conduit, vessel and the like, in contact with material to be electrified; with means of moving and renewing the materials at the contact; with means of attemperating the material and the conduit and the like with cut-out switch, voltmeter, ammeter and resistance in the earth line of the circuit; with insulator supports for all connecting vessels, pipes and other apparatus; with dielectric joints in all connecting pipes separating such from the electrifier vessel. 85
- 25 24. An electrifier apparatus comprising a direct current metallic circuit of which the earth forms no part; with means of earthing one terminal thereof and of connecting the other terminal to a conductor plate and the like in contact with material to be electrically treated; with pole changing switch, a circuit breaker, voltmeter and ammeter, and resistance in the circuit; with insulator supports for all apparatus and connections. 90
- 30 25. An electrifier tray of good conducting material for the purpose stated with means of fastening therein materials to be treated; with dielectric handles; with insulator supports; with means of electrically connecting the tray with one pole of a direct current supply the other pole being earthed. 95
- 35 26. An electrifier metal comb, for the purpose stated, with dielectric covered handle, with means of electrically connecting the comb through a movable insulated extension wire with one pole of a direct current supply, the other pole being earthed; with means of attemperating the comb; with means of combing with said comb thus electrically connected a fur, pelt and the like. 100
- 40 27. An electrifier rubbing plate for the purpose stated, of good conducting material; with roughened surface; with insulator supports; with means of electrically connecting the plate with one pole of a direct current supply, the other pole being earthed; with means through dielectric handling clamps and the like of passing a fur and the like, in contact with said plate, to and fro; with means of attemperating said plate; all under insulated conditions. 105
- 45 28. In an apparatus as described, an electrifier plate and the like connected by a superior conductor wire and the like with one terminal of a d. c. supply the other terminal being earthed, and made of resistor material and in shape permitting contact therewith of a fur and other solid materials, with means of attemperating the plate, tray and the like; all under insulated conditions. 110
- 50 29. In an apparatus of the nature described, a closed vessel on insulator supports; with means of placing therein and withdrawing therefrom intermittently solid materials to be dyed; with means of creating a near-vacuum in the vessel and solid material contents; with means of circulating through the vessel, under pressure continuously and intermittently, liquids and gases; with means of attemperating the solids, liquids and gases; with means of electrifying with one sign only the solids and likewise with opposite sign and different potential, the liquids and gases; all under insulated conditions. 115
- 55 30. In an apparatus of the nature described a closed vessel on insulator supports; with means of opening and hermetically sealing the vessel; with means of placing therein solid materials to be treated; with means of creating a near-vacuum in the vessel holding solid materials; with means of forcing with pressure into and out 120
- 60 65 125 130

of the sealed vessel, liquids and gases; with means of attemperating the said solids, liquids and gases; with means of electrifying with one sign only the said solids, liquids and gases; all under insulated conditions.

31. In an apparatus as described, a resistance in the circuit and as an electrifier conduit plate and the like, constructed of a closely connected succession of metallic thermo-electric couples, placed in a d. c. circuit, whereof one pole is grounded, the

couples being connected in series in the non-grounded terminal line with the current flowing therethrough in the same direction as the thermo-electric current would flow at the hot junction. 11

In testimony whereof I have hereto affixed my hand in the presence of two witnesses.

JACOB E. BLOOM.
